UNITED STATES PATENT OFFICE.

LAWRENCE ABRAHAM, OF NEW YORK, N. Y.

CONVEYER.

SPECIFICATION forming part of Letters Patent No. 777,171, dated December 18, 1904.

Application filed May 17, 1904. Serial No. 208,364. (No model.)

To all whom it may concern:

Be it known that I, LAWRENCE ABRAHAM, a citizen of the United States, and a resident of the borough of Brooklyn, county of Kings, 5 city and State of New York, have invented certain new and useful Improvements in Conveyers, of which the following is a specification.

My invention relates to conveyers for delivering parcels or goods at different floors of 10 a building, and has for its object to provide a simple device which may be used both in ascending and descending and which will automatically discharge the parcels or goods at the various floors for which said parcels or 15 goods are intended.

The invention will be fully described hereinafter and the features of novelty pointed out in the appended claims.

Reference is to be had to the accompanying 20 drawings, in which—

Figure 1 is a diagrammatic elevation of a conveyer with my invention applied thereto and with parts in section. Fig. 2 is a plan. Fig. 3 is an enlarged fragmentary side view 25 of the conveyer, with parts in section, as it ascends. Fig. 4 is a front view of the same. Fig. 5 is an enlarged fragmentary side view of the conveyer, with parts in section, as it descends; and Fig. 6 is a front elevation thereof.

30 A B are rollers journaled upon shafts A' B', respectively, and arranged to support the traveling belt C. Power may be applied to the rollers in any suitable manner. Upon the belt C pivot-blocks D are secured at spaced 35 intervals in any convenient manner—as, for instance, by riveting. Upon these blocks D are pivotally secured carriers comprising skeleton frames E, having arms E' and E'' for steadyng the said frames and standards F 40 and F' at the outer edges of said skeleton frames. Shelves G and G' are hinged at H and H' upon the said standards F and F'. The said shelves G and G' are connected by a rod I, the purpose of which will be more fully de- 45 scribed hereinafter. To prevent undue wear upon the belt C, reinforcing-strips C', of metal or other material, are secured to the said belt C at the points where the ends of the arms E' and E'' will abut against said strips.

50 J is a chute situated one on each floor of

the building, upon which parcels are adapted to be discharged as the conveyer ascends.

K is an extension of the chute J, pivoted at K' and having attached to it a weight K'.

L represents rollers which may be mounted upon suitable framework, (not shown,) one set for each floor, and M represents arms forming part of or secured to the shelf G, which extend outward so as to be in a position to engage the rollers L as the belt ascends. The 60 chutes J, however, are not in the path of the arms M. (See Fig. 2.) Similar arms N extend from the inner edge of the shelf G', said arms being arranged to engage stationary cam-surfaces O as the belt descends.

P represents belt conveyers, one for each floor, traveling over rollers P', upon which the parcels are adapted to be discharged as the conveyer descends. Upon the shaft of the rollers P' is pivoted a short chute Q, having 70 a weight Q' secured thereto.

It will be understood that the arms M N of the shelves G G', respectively, are so arranged that no two sets of arms M and N engage the same rollers L in ascending or cams O in descending. (See Fig. 2.) Thus the shelves G and G' may be marked to correspond to the floors upon which they are intended to discharge the parcels or goods. In a direct line with each of the rollers L and cams O on the inside of the belt C are placed rollers R, extending 75 across the width of the said belt and suitably mounted on stationary framework. (Not shown.) The purpose of these rollers R is to prevent the belt C from bulging inward and discharging the goods or parcels prematurely. Similar rollers S for a similar purpose are so placed that they will be just opposite to the lower ends of the arm E' in ascending and opposite E' in descending.

80 The operation of the device is as follows: Power is applied in any suitable manner to drive the conveyer, the shelves all being in the position indicated at the upper part of Fig. 1 and in dotted lines in Fig. 3. It will be noticed that all of these shelves incline toward the belt, each shelf being marked to correspond to one floor of the building—that is, the shelf which is to discharge at the first floor is marked with a "1" and the one intended to 85 90 95 100

discharge at the second floor with a "2," and so on—there being two shelves for each floor, one to discharge in ascending and the other in descending. If parcels or goods are now placed on the shelf marked "1," the said goods will remain on said shelf until it reaches the first floor. As soon as the outer edge of the shelf reaches the part K of the chute J the said part K will tilt on its pivot (see dotted lines, Fig. 3) and be held in this position until the shelf has passed, whereupon the part K will be swung back to its initial position under the influence of the weight K', it being understood that the pivot K' is constructed as a rule-joint and capable of swinging only in one direction from its normal position. Now as the shelf continues to ascend the arms M will contact with the roller L on the first floor, and the shelf G will be swung on its pivot H to the position shown in the lower part of Fig. 1 until a certain angle is reached, whereupon the goods or parcels will slide off the shelf and will be deposited on the chute J, which may lead to a suitable table or bin. It will be understood that the inner edges of the parts K are inside of the outer edges of the shelves G, or, in other words, the part K is overlapped by the discharge end of the shelf G. The parts K are hinged for the sole purpose of allowing them to be swung out of the path of the shelves. The rollers L are so disposed that the tipping of the shelves will not commence until the part K has resumed its initial position. To prevent the shelf G from being swung too far, the said shelf is connected by a rod I to the shelf G', which will thus act as a stop against the lower portion of the frame E. As the conveyer continues to ascend the arms M will ride past the rollers L and the shelves will drop back to their original position by their own weight. As before pointed out, the rollers L are so spaced on each floor and the arms intended to engage them are spaced to correspond, so that no two sets are alike and so that the arms of the shelf will only engage the rollers on the floor on which it is intended to discharge and will pass all others without engaging them. In descending the shelves G' become the upper ones, and the arms N engage the cams O, and the shelves G' are thus tilted to discharge the goods upon the conveyer P in the same manner as explained in regard to the shelves G, the shelves G in this case acting as a stop to prevent the shelves G' from being tilted too far, the shelves returning to their initial position as soon as they pass the cams O. As the shelves continue to descend the outer edges of the shelves G will first abut against the part Q and swing the same on its pivot P' and pass on, and then the outer edge of the shelves G' will engage the part Q and again swing it on its pivot and also pass on, the said part Q being returned by its weight Q'. It will be understood that the cams O are so arranged that the shelves G' are fully tilted to

discharge before the outer edges of the shelves G touch the part Q. The purpose of the part Q is the same as explained in regard to the part K, and the cams O and the arms N are arranged exactly as the arms M and the rollers L—that is, so that each shelf will discharge only on the floor for which it is marked and on which the spacing of the cams corresponds to the spacing of the arms N. It will be understood that all of the stationary parts are mounted on suitable framework, which I have omitted for the sake of clearness.

While I have shown what I consider at present the best means of carrying out my invention, I desire it to be distinctly understood that various modifications may be made without departing from the nature of my invention.

I claim and desire to secure by Letters Patent—

1. The combination with a traveling conveyer, of frames secured to said conveyer, a plurality of shelves movably secured to each of said frames, means for causing said shelves to discharge their contents at predetermined points, and a connection between two shelves carried by the same frame for causing one of said shelves to act as a stop to limit the movement of the other shelf at the moment of discharge.

2. The combination with a traveling conveyer, of a frame movably secured to said conveyer, standards on said frame, shelves pivoted to said standards, means for causing said shelves to discharge their contents at predetermined points and a connection between said shelves for causing one of said shelves to act as a stop to limit the movement of the other shelf at the moment of discharge.

3. The combination with a traveling conveyer, of frames movably secured to said conveyer, a plurality of shelves pivotally secured to each of said frames, and supports adapted to receive articles discharged from said shelves, said supports comprising a movable part arranged to be engaged by the shelves and moved out of the path of said shelves and means for causing said movable part to be returned to its initial position so that the said movable part will be overlapped by the shelves at the moment of discharge.

4. The combination with a traveling conveyer, of shelves secured thereto, a second conveyer arranged at an angle to the first-named conveyer and in-receiving relation to said shelves, and a pivoted chute arranged in the path of the shelves and overlapped by the shelves at the moment of discharge and arranged to be moved out of the path of the shelves by the shelves themselves.

5. The combination with a traveling conveyer, of frames movably secured thereto, steadyng - arms extending at substantially right angles from said frames, reinforcing strips on said conveyer adjacent to the ends of

said steadyng - arms, a plurality of shelves movably secured to each of said frames, means for causing said shelves to discharge their contents at predetermined points and means arranged opposite to the ends of said steadyng-arms for preventing the belt from bulging inwardly at the moment of discharge.

6. The combination with a traveling conveyer, of frames secured to said conveyer, a plurality of shelves movably carried by each of said frames, each shelf being provided with arms arranged to travel in different paths, stationary discharge devices arranged to come in contact with the corresponding arms to move the shelves relatively to the conveyer, and a connection between two shelves carried by the same frame for causing one of said shelves to act as a stop to limit the movement of the other shelf.
- 20 7. The combination with a traveling conveyer having ascending and descending runs, of carriers arranged in pairs and movably secured to said conveyer, said carriers being provided with members which are differently placed in unlike pairs of carriers, and station-

ary discharge devices arranged respectively in the paths of said members adjacent to the ascending and descending runs of the conveyer, those discharge devices which are adapted to engage the said members of like pairs of carriers, being arranged at approximately the same level both at the ascending and at the descending run of the conveyer.

8. The combination with a traveling conveyer, of shelves secured thereto, and stationary supports adapted to receive articles discharged from said shelves, said supports comprising a movable part arranged in the path of the shelves and overlapped by the shelf at the moment of discharge and adapted to be moved out of the path of the shelves by the shelves themselves.

In testimony whereof I have hereunto signed my name in the presence of two subscribing witnesses.

LAWRENCE ABRAHAM.
